UNITED STATES PATENT OFFICE.

JAMES CHRISTIE JENKINS, OF KAYFORD, WEST VIRGINIA.

FIRE BOX.

Application filed August 30, 1920. Serial No. 406,832.

To all whom it may concern:

Be it known that I, JAMES CHRISTIE JENKINS, a citizen of the United States, residing at Kayford, in the county of Kanawha and State of West Virginia, have invented a new and useful Fire Box, of which the following is a specification.

It is the object of this invention to provide novel means whereby air may be introduced into the fire box of a locomotive, for the purpose of enhancing combustion, the construction being such that air may be heated before being delivered into the products of combustion, the air being discharged at a point where it will be most effective.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in vertical section, a portion of a locomotive fire box wherein the device forming the subject matter of this application has been mounted; Figure 2 is a section taken approximately on the line 2—2 of Figure 1; Figure 3 is an elevation showing one of the bricks; Figure 4 is a section on the line 4—4 of Figure 3; and Figure 5 is a top plan showing a modification in one of the bricks, parts appearing in section.

Although the invention may be embodied in boilers of widely different sorts, there is shown in the drawings, by way of illustration, the shell 1 of a locomotive boiler. The numeral 2 marks the crown sheet, the forward wall of the fire box appearing at 3, the numeral 4 designating the rear wall of the fire box, and the sides of the fire box being shown at 9. The grate appears at 5. Rearwardly and upwardly extended supports 6, which may be the ordinary water tubes, connect the forward wall 3 of the fire box and the rear wall 4 thereof. The space between the side walls 9 and the outermost supports 6 is filled by lines of outer bricks 7, the space between the remaining supports

being filled by inner bricks 10. Forward bricks 8 are disposed against the forward wall 3, in front of the bricks 7 and 10. The bricks are shaped, wherever necessary, as indicated at 11, to correspond with the cross sectional contour of the supports 6, the bricks terminating, as indicated by the numeral 20 in spaced relation to the rear wall 4. The bricks 7 and 10 have passages 12, alined with tapered passages 14 in the forward bricks 8, the various passages coacting to define flues. Each forward brick 8 is provided with a reduced neck 15 received within a thimble 16 mounted in the lower forward portion 17 of the boiler shell and in the lower portion of the forward wall 3 of the fire box, the thimble 16 communicating with the atmosphere.

In practical operation, air enters through the thimbles 16 and through the necks 15 into the flues defined by the passages 14 and 12 in the bricks 7, 10 and 8. The air is heated to a high degree as it traverses the flues above alluded to, the heated air being delivered into the products of combustion at the point indicated by the numeral 20 in Figure 1 of the drawings. The air, discharged in a heated condition at the point above mentioned, results in a thorough consumption of the fuel. It is to be observed that the forward bricks 8 abut against the lower portion of the forward wall 3, it being impossible for the products of combustion to cut directly upward, in front of the foremost bricks 8.

As shown in Figure 5, the brick 10^a may be provided at one end with a flared seat 19, communicating with the passage 12^a and adapted to receive a projection 18 on an adjoining brick.

Having thus described the invention, what is claimed is:

The combination with the forward and rear walls of a fire box, supports extended between the rear wall and the forward and inclined downwardly toward the forward wall, and the shell of a boiler; of a thimble mounted at its ends in the forward wall and in the shell and opening through the forward wall and the shell, alined forward and rear bricks resting directly upon the supports, the lower longitudinal edges of the bricks being cut away to receive the supports and to conform to the cross section thereof, each rear brick having a single longitudinal passage of large size compared with the cross

section of the brick, but of such a size as to leave solid portions at each side of each rear brick, said solid portions being thicker than those portions of the bricks which lie between the passages of the bricks and the upper and lower surfaces of the bricks, and a forward brick against which the rear bricks thrust as they tend to slide down the supports, the forward brick abutting against the forward wall and having a reduced projecting neck received in the thimble, the forward brick having a passage communicating with the passages of the rear bricks, and tapered from the rear end of the forward

brick to the neck, the passage of the forward brick defining solid portions at the sides of the forward brick, said solid portions of the forward brick increasing in thickness from their rear ends thereby to bear the thrust transmitted from said solid side portions of the rear bricks.

In testimony that I claim the foregoing as my own, I have hereto affixed my signature in the presence of two witnesses.

JAMES CHRISTIE JENKINS.
